Primary Examiner — T Chase Nelson*Assistant Examiner* — Sydney Margaret Parsley(74) *Attorney, Agent, or Firm* — Stephen D. Carver(57) **CLAIM**

The ornamental design for a portable and collapsible folding hunting seat, as shown and described.

DESCRIPTION

FIG. 1 is an upper, left front isometric view of my new portable and collapsible folding hunting seat, showing the new design;

FIG. 2 is a lower right rear isometric view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a front elevational view thereof; and,

FIG. 8 is a rear elevational view thereof.

Broken lines in the drawings form no part of the claimed design but show environment.

1 Claim, 6 Drawing Sheets(56)
